DOCUMENT NUMBER

D 15583

UNITED STATES PATENT OFFICE.

RICHARD W. BAINBRIDGE, OF BROOKLYN, NEW YORK.

DESIGN FOR WRITING-PAPER, &c.

SPECIFICATION forming part of Design No. 15,583, dated December 2, 1884.

Application filed August 20, 1884. Term of patent 3½ years.

To all whom it may concern:

Be it known that I, RICHARD W. BAINBRIDGE, of the city of Brooklyn, in the county of Kings and State of New York, have originated and produced a new Design for Writing-Paper, Envelopes, and Cards, of which the following is a specification.

My design for writing-paper, envelopes, and cards consists in paper having the representation of lines of hem-stitching extending parallel with its edges.

The design also consists in paper having the representation of lines of hem-stitching extending parallel with its edges and terminating at the edges, and having notches in the edges at the points of termination of said lines.

In the accompanying drawings, Figure 1 is a sheet of note-paper embodying my design. Fig. 2 is the back portion of an envelope embodying the design, and Fig. 3 is a card embodying the design.

Similar letters of reference designate corresponding parts in the several figures.

A designates the paper which embodies my design.

In Fig. 2 the back of the envelope has its closing-flap A* folded down and secured.

The paper shown in Fig. 1, and the paper from which the envelope shown in Fig. 2 is formed, as well as the card shown in Fig. 3, have the representation of lines *a* of hem-stitching extending parallel with their edges. These lines extend from edge to edge of the paper, crossing each other at *a**, and in the edges, at the points of termination of the lines *a*, are notches *b*.

What I claim, and desire to secure by Letters Patent, is—

1. The design for writing-paper, envelopes, and cards, consisting in paper having the representation of lines *a* of hem-stitching extending parallel with its edges, substantially as shown and described.

2. The design for writing-paper, envelopes, and cards, consisting in paper having the representation of lines *a* of hem-stitching extending parallel with the edges and terminating at the edges, and having notches *b* in the edges at the points of termination of the lines *a*, substantially as shown and described.

RICHARD W. BAINBRIDGE.
